UNITED STATES PATENT OFFICE

145,882

DESIGN FOR A SLIPPER OR SIMILAR ARTICLE

Gustav Cohn, New York, N. Y.

Application August 14, 1946, Serial No. 132,511

Term of patent 3½ years

(Cl. D7—7)

To all whom it may concern:

Be it known that I, Gustav Cohn, a citizen of the United States of America, residing in New York city, county of New York, and State of New York, have invented a new, original, and ornamental Design for a Slipper or Similar Article, of which the following is a specification, reference being had to the accompanying drawing, forming part thereof, wherein the figure is a front per-

spective view of a slipper or similar article showing my new design.

The opposite side of the slipper or similar article is identical in appearance to the side shown.

I claim:

The ornamental design for a slipper or similar article, substantially as shown and described.

GUSTAV COHN,
